UNITED STATES PATENT OFFICE.

PHILLIP BAKER, OF MALDEN, MASSACHUSETTS.

MATTRESS-FILLING MACHINE.

Application filed March 6, 1922. Serial No. 541,484

To all whom it may concern:

Be it known that I, PHILLIP BAKER, a subject of Lithuania, residing at Malden, in the county of Middlesex and State of Massachusetts, have invented new and useful Improvements in Mattress-Filling Machines, of which the following is a specification.

This invention relates to a machine for filling mattresses with down, floss and the like, and while the machine is particularly adapted for that purpose, the same may also be utilized for filling other articles such as pillows, comforters and the like with floss, down or feathers.

15 The object of the invention is to provide a machine of the character set forth in which a thorough beating up and circulation of the filling material may be obtained prior to the time when the machine is being used to fill a mattress, and after this beating up and circulation of the filling material has been completed, the machine may be quickly and easily changed to fill a mattress with the filling material.

25 The object of the invention is further to provide a machine for the purposes hereinbefore set forth which shall be simple and effective in its construction and operation, and particularly the object of the invention 30 is to provide a machine of the character hereinbefore set forth which will prevent clogging of the filling material in the machine, whether the machine be operated to fill the mattress, or whether it be operated to beat up the material and circulate the same prior to the mattress filling operation.

The invention consists in the combination and arrangement of parts set forth in the following specification and particularly 40 pointed out in the claims thereof.

Referring to the drawings:

Figure 1 is a front elevation of the machine partly broken away and shown in section.

45 Fig. 2 is a plan view of the same.

Fig. 3 is a sectional elevation taken on line 3-3 of Fig. 1.

50 Fig. 4 is a sectional detail plan, somewhat diagrammatic in its nature, taken along the line 4-4, Fig. 1, only a portion of the radial arms of the shaft 26 being shown for the sake of more clearly illustrating the construction and arrangement of the rotary and stationary arms.

55 Like numerals refer to like parts throughout the several views of the drawings.

In the drawings, 5 is a receptacle for filling material the same consisting of a cylindrical base portion 6, a conical intermediate portion 7 increasing in diameter from the bottom to the top thereof and a conical portion 8 decreasing in diameter from the bottom thereof to the top of the receptacle. At the bottom of the conical portion 7 is a grate 9 and underneath this grate is a pit adapted to receive refuse material and this pit is provided with a door 10 whereby said refuse material may be removed from the pit. A door 11 is provided in the conical portion 7 of the receptacle and this door is provided with a hopper 12 having a cover 13 hinged to the door 11. Filling material may be introduced into the receptacle 5 through the hopper 12. A screen 14 is provided in the top of the conical portion 8 of the receptacle. A circulating fan 15 is connected by an intake pipe 16 to the lower part of the conical portion 7 and a return pipe 17 connects said fan to the upper portion of the receptacle.

In the present embodiment of my invention the return pipe is connected to the conical portion 8 and extends downwardly therefrom and entirely through the receptacle 5 projecting outwardly therefrom to form a projecting open, outer end 18. A portion 19 of the return pipe 17 which extends through the receptacle 7, has an opening 20 therein which leads into the receptacle 5. A damper 21 is fast to a shaft 22 which extends transversely of the receptacle 7 and is provided at its outer end with an arm 23 constituting a handle whereby the damper 21 may be rotated to open the portion 19 of the return pipe or to close the same. When the damper 21 is positioned as illustrated in the drawings, the opening 20 is closed and when the damper is turned upwardly so that the opening 21 opens into the receptacle 5, then the pipe 19 is closed by said damper.

An annular flange 24 is provided on the outer end of the projecting portion 18 of the return pipe 17 and this portion of the return pipe constitutes a nozzle to which the open end portion of the mattress is fastened while the filling operation is in process.

The material used for filling the mattresses, such as silk floss, is first thoroughly beaten up in the receptacle 5 and this is accomplished by means of an agitating device or beater 25 consisting of a shaft 26 with arms 27 projecting radially therefrom and arranged in a series of helices. These arms,

during the rotation of the shaft 26, pass between stationary arms 40 which are rigidly fastened to segmental plates 41 which are fastened to the inside of the receptacle 5 as illustrated in Figs. 1 and 4. As the shaft is rotated it will be seen that the arms 27 and 40 co-act to thoroughly agitate and beat up the filling material. It will further be seen that the rotary member is located just 10 above the grate 9 and in alignment with the entrance to the intake pipe 16 so that said rotary member will assist in feeding the filling material into the inlet end of the intake pipe. The intake pipe 16 is provided 15 with a hopper 28 having a cover 29 which may be opened for the purpose of inspecting the condition of the filling material while it is passing through the pipe 16.

The circulating fan 15 is rotated by means 20 of a pulley 30 fast to the shaft 31 of said circulating fan and connected by a belt 32 to a pulley 33 fast to the shaft 34 of an electric motor 35. Said electric motor shaft 34 has another pulley 36 fast thereto and connected by a belt 37 to a pulley 38 fast to the shaft 26 of the beater. A damper 39 is provided in the pipe 16 adjacent the receptacle 5 whereby said pipe may be opened or closed.

The general operation of the mechanism 30 hereinbefore specifically described is as follows:—Assuming the filling material to have been inserted within the receptacle 5 through the hopper 12 and that the mattress to be filled is fastened in a manner well known to those skilled in the art to the outer end of the portion 18 of the return pipe 17, the first operation to be performed is to beat up the floss with the beater 25 and this is done by first closing the damper 39 and closing 40 the opening 20 by means of the damper 21. After the floss has been thoroughly beaten up the damper 39 is opened and the damper 21 is turned across the portion 19 of the pipe 17, and the fan will then operate to cause the 45 silk floss to circulate and also to be further beaten up, the circulation of the floss taking place from the receptacle 5 through the pipe 16 through the blower 15 and through the return pipe 17 and through a portion of the 50 pipe 19 and outwardly therefrom through the opening 20 into the receptacle again. This circulation of the material continues until, by inspection through the hopper 28, the silk floss is found to be in proper condition 55 to be fed into the mattress, whereupon the damper 21 is turned to close the opening 20 and the blower draws the floss out of the receptacle 5 and forces it through the return pipe 17 and through the portion 19 of said 60 return pipe out of the outlet end 18 of said pipe and into the mattress. As soon as the mattress is filled, the operation hereinbefore described is repeated.

It will be understood that the shafts of 65 the circulating fan and the beater are rotat-

ed by the electric motor 35 through the belts 32 and 37 respectively.

I claim:

1. A machine for filling mattresses and the like having, in combination, a receptacle 70 for filling material, a circulating fan, intake and return pipes connecting said fan to said receptacle, said return pipe extending from said fan through said receptacle and terminating in an open outer end, said return 75 pipe being provided within said receptacle with an opening into said receptacle and a damper in said return pipe adjacent said opening whereby that portion of said return pipe extending through said receptacle 80 may be alternately, closed to said receptacle and opened therethrough to said open, outer end, or vice versa.

2. A machine for filling mattresses and the like having, in combination, a receptacle 85 for filling material, a circulating fan, intake and return pipes connecting said fan to said receptacle, said return pipe extending from said fan through said receptacle and terminating in a projecting open outer end, 90 said return pipe being provided within said receptacle with an opening into said receptacle and a damper in said return pipe adjacent said opening whereby that portion of said return pipe extending through said 95 receptacle may be alternately, closed to said receptacle and opened therethrough to said open, outer end, or vice versa, and means to operate said damper from outside said receptacle.

3. A machine for filling mattresses and the like having, in combination, a receptacle 100 for filling material, a circulating fan, intake and return pipes connecting said fan to said receptacle, said return pipe extending 105 from said fan through said receptacle and terminating in an open outer end, said return pipe being provided within said receptacle with an opening into said receptacle and a damper in said return pipe adjacent 110 said opening whereby that portion of said return pipe extending through said receptacle may be alternately, closed to said receptacle and opened therethrough to said open, outer end, or vice versa and means within 115 said receptacle to agitate said material.

4. A machine for filling mattresses and the like having in combination, a receptacle 120 for filling material, a circulating fan, an intake pipe leading out of the lower portion of said receptacle to said circulating fan, a return pipe leading into the upper portion of said receptacle connecting said fan to said receptacle and extending downwardly through said receptacle and terminating in 125 an open outer end, said return pipe being provided within said receptacle with an opening into said receptacle and a damper in said return pipe adjacent said opening whereby that portion of said return pipe 130

extending through said receptacle may be alternately, closed to said receptacle and opened therethrough to said outer open end, or vice versa.

- 5 5. A machine for filling mattresses and the like having, in combination, a conical receptacle for filling material, said conical receptacle increasing in diameter from the bottom toward the top thereof, a circulating 60
10 fan, an intake pipe leading out of said receptacle adjacent the lower end of the conical portion thereof, a return pipe leading into said receptacle adjacent the upper end thereof and extending from said fan 65
15 through said receptacle and terminating in an open outer end, said pipes connecting said fan to said receptacle and said return pipe being provided within said receptacle with an opening into said receptacle and a 70
20 damper in said return pipe adjacent said opening whereby that portion of said return pipe extending through said receptacle may be alternately, closed to said receptacle and opened therethrough to said open outer end, 75
25 or vice versa.

6. A machine for filling mattresses and the like having, in combination, a receptacle for filling material, a circulating fan, intake and return pipes connecting said fan 80
30 to said receptacle, said return pipe extending from said fan through said receptacle and terminating in an open outer end, said return pipe being provided within said receptacle with an opening into said receptacle 85
35 and a damper in said return pipe adjacent said opening whereby that portion of said return pipe extending through said receptacle may be alternately, closed to said receptacle and opened therethrough to said open, outer end, or vice versa and a rotary 90
40 member located adjacent the inlet end of said intake pipe and adapted to agitate material located within said receptacle and to assist the feeding of said material to said 95
45 intake pipe.

7. A machine for filling mattresses and the like having, in combination, a receptacle for filling material, a circulating fan, intake and return pipes connecting said fan 100
50 to said receptacle, said return pipe extending from said fan through said receptacle and terminating in an open outer end, said return pipe being provided within said receptacle with an opening into said 105
55 receptacle and a damper in said return pipe adjacent said opening whereby that portion

of said return pipe extending through said receptacle may be alternately closed to said receptacle and opened therethrough to said open, outer end, or vice versa, a 60
65 screen opening into the top of said receptacle, a rotary member located adjacent the inlet end of said intake pipe beneath said return pipe and adapted to agitate said material and assist in feeding the same to 70
70 said intake pipe, and a grate in said receptacle located beneath said rotary member.
8. A machine for filling mattresses and the like having, in combination, a receptacle for filling material, a circulating fan, intake and return pipes connecting said fan 75
75 to said receptacle, said return pipe extending from said fan through said receptacle and terminating in an open outer end, said return pipe being provided within said receptacle with an opening into said receptacle 80
80 and a damper in said return pipe adjacent said opening whereby that portion of said return pipe extending through said receptacle may be alternately, closed to said receptacle and opened therethrough to said open, outer end, or vice versa, means within 85
85 said receptacle beneath said return pipe and adjacent to the outlet end of said inlet pipe adapted to agitate said material, a door opening into said receptacle and a hopper on said door whereby material may be fed into said receptacle.

9. A machine for filling mattresses and the like having, in combination, a receptacle 90
90 for filling material, a circulating fan, intake and return pipes connecting said fan to said receptacle, said return pipe extending from said fan through said receptacle and terminating in an open outer end, said return pipe being provided within said receptacle with an opening into said receptacle 95
95 and a damper in said return pipe adjacent said opening whereby that portion of said return pipe extending through said receptacle may be alternately, closed to said 100
100 receptacle and opened therethrough to said open, outer end, or vice versa, and a beater located within said receptacle and adapted to agitate the material therein.

In testimony whereof I have hereunto set my hand in presence of two subscribing witnesses.

PHILLIP BAKER.
